UNITED STATES PATENT OFFICE.

ARTHUR TREVOR DAWSON AND GEORGE THOMAS BUCKHAM, OF LONDON, ENGLAND,
ASSIGNORS TO VICKERS SONS & MAXIM LIMITED, OF LONDON, ENGLAND.

SIGHTING APPARATUS FOR ORDNANCE.

No. 913,705.

Specification of Letters Patent. Patented March 2, 1909.

Application filed October 23, 1907. Serial No. 398,717.

To all whom it may concern:

Be it known that we, ARTHUR TREVOR DAWSON, lieutenant Royal Navy, director and superintendent of Ordnance Works, and 5 GEORGE THOMAS BUCKHAM, engineer, both subjects of the King of Great Britain, residing at 32 Victoria street, Westminster, in the county of London, England, have invented certain new and useful Improvements Relating to Sighting Apparatus for Ordnance, of which the following is a specification.

This invention relates to sighting apparatus of the kind in which there is a range dial and a pointer so arranged that in imparting angular displacement of the dial relatively to the pointer the proper elevation will be given to the sight to accord with a particular range. We have already devised various forms of apparatus of this kind in 10 which the pointer can be actuated or set from a distance by electrical means (an electric motor for example) controlled from the place or station whence the information relating to the sighting is transmitted, the dial 15 being moved by hand gearing by the sight setting number of a gun's crew to bring a setting mark or spot thereon into coincidence with the pointer, in order to set the sight for the particular range indicated by the position of the pointer. We have also devised 20 means whereby in the act of setting the range dial relatively to the pointer, a correction will be automatically made to compensate for alterations in the muzzle velocity and 25 changes in the temperature of the charges by changing the position of the pointer, so that in setting the range dial a greater or less angular movement will be imparted to the dial in bringing a particular graduation or 30 mark thereon into coincidence with the pointer. These compensating means we term a "calibrating" device.

It is the chief object of our present invention to modify the construction of the said 45 calibrating device and combine it with sighting apparatus having the aforesaid electrically actuated pointer.

Our present invention is particularly, although not exclusively, intended for use 50 with duplex sights of the well known cross-connected kind.

We will describe our invention with reference to the accompanying drawings, in which:—

Figures 1 to 6 illustrate the improved form 55 of the calibrating device combined with sighting apparatus in which the electric motor for actuating the pointer is mounted in a casing that is angularly displaceable about the axis of the range dial; Fig. 1 being a face 60 view; Fig. 2 a vertical section, and Fig. 3 a horizontal section. Figs. 4, 5 and 6 are diagrammatic views showing the parts in several different positions. Figs. 7 and 8 are detail views of the apparatus to an enlarged 65 scale.

A is the range dial, B the electrically controlled pointer, B' the electric motor for actuating the pointer, and C^x the actuating wheel of the hand gearing for setting the 70 range dial in accordance with the movements of the pointer, the setting being effected by causing the setting mark or spot a to follow the movements of the pointer, and in thus moving to alter the elevation of 75 the sight. The range dial is loosely mounted on a bearing A⁴ forming part of the range dial casing A⁵ and is connected by suitable gearing to the pinion A⁶ of the sight elevating gear which may be of any ordinary type. 80 The sight elevating worm wheel A⁷ is integral with a toothed wheel A⁸ that gears with a wheel A⁹ keyed to the shaft of the elevating pinion A⁶. The weight of the sight acts on the worm wheel A⁷ through the intervention 85 of the toothed wheels A⁸ and A⁹, and thus takes up any backlash existing between the rack and the range dial. The said calibrating device comprises a cam or spiral groove a' formed on or in the dial for actuating a 90 roller d' situated at the end of one arm d² of a bell-crank lever which is adapted to swing about an axis or bearing d on the dial casing. The other arm d³ of the bell crank lever is arranged to receive a sliding block d⁴ which 95 is adapted to be shifted and secured in any desired position on this arm. The sliding block d⁴ is provided with an index piece d^{4x} (Fig. 7) which may be adjusted by means of a screw d^{3x}. A scale is provided on the 100 block to indicate the position in which the index piece has to be set for different muzzle velocities, and the arm d³ is provided with temperature curves which are carefully calculated to give the correct position for the 105 sliding block d⁴. The electric motor is carried by a casing B⁴, which is pivoted on an extension A^{4x} of the bearing A⁴, and is

capable of bodily turning about the axis of the range dial. The spindle b^3 carrying the motor-driven range pointer B passes through the center of the bearing A^4 , A^{4x} and at its 5 inner end is furnished with a worm wheel b^4 that gears with a worm b^5 which is driven from the motor B' through suitable gearing b^6 . The motor casing is connected to the said sliding block d^4 by a link d^5 which is 10 preferably hinged to an arm B^6 on said motor casing.

When the motor is actuated by an electric current from the distant or sending station, it drives the range pointer B through the 15 worm gearing b^4 b^5 and causes it to move angularly about the dial A until it reaches a position corresponding to the required range. The sight is then elevated by the hand wheel C^x and the sighting gear until 20 the setting mark or spot a on the dial arrives opposite to the range pointer. During this movement, the spiral groove a' of the range dial imparts movement to the bell-crank lever d^2 d^3 , which in turn imparts angular 25 movement to the motor casing B' through the link d^5 , the amplitude of such movement depending upon the position of the sliding block d^4 on the arm d^3 of the bell-crank lever. If the block is moved inward towards the 30 pivot d of the bell-crank lever, so as to bring the center of the contiguous end d^{5x} of the link d^5 into coincidence with the center of the said pivot as represented in Figs. 4 and 35 5, the motion imparted to the bell-crank lever by the spiral groove a' when the range dial is angularly displaced by the hand wheel C^x from the position shown in Fig. 4 to that shown in Fig. 5, will not affect the position of the motor casing B' and no 40 additional movement will be given to the pointer. If however the sliding block d^4 be moved outward or away from the pivot d of the bell-crank lever, as shown in Figs. 1 and 6, the motion imparted to the latter by 45 the spiral groove a' when the range dial is angularly displaced from the position shown in Fig. 1 to that shown in Fig. 5, will be transmitted to the motor casing by the said link d^5 (see Fig. 6). The extent of this 50 movement of the motor casing will depend upon the distance the sliding block has been previously shifted from the pivot d , and will have the effect of increasing the angular movement imparted to the pointer by the 55 motor. In this manner the elevation given to the sight during the movement of the range dial to bring the setting mark a opposite the range pointer, will be increased and the requisite correction for the fall in the 60 muzzle velocity and the change in charge-temperature will be automatically effected. To make the necessary corrections the index piece d^{4x} is first set to the muzzle velocity scale and the sliding block then moved along 65 the arm d^3 until the arrow d^6 on the index

piece d^{4x} touches the required temperature curve. This block d^4 is secured in position on the arm d^3 by means of the screw d^7 .

The range graduations are preferably formed upon a separate adjustable ring 70 attached to the face of the dial A. These graduations are not required for ordinary use and are only provided to meet cases of emergency, as for example the failure of the electrical transmitting apparatus. The said 75 graduations are, so long as the electric motor is in working order, kept covered by a thin detachable steel plate on which is engraved the setting mark a . In some cases the graduations are engraved on one side of the 80 detachable plate and the setting mark a on the other side, so that by reversing the plate either the graduations or the setting mark can be exposed to view.

Figure 7 shows the calibrating device set 85 for a muzzle velocity of 2,525 feet per second and a charge temperature of 75 degrees.

What we claim and desire to secure by Letters Patent of the United States is:—

1. In sighting apparatus for guns, the 90 combination with the range dial and its pointer, of means for actuating said pointer, from a distance, hand actuated means for setting the range dial with respect to the pointer and changing the elevation of the sights, and means for automatically varying the relative movement of the range dial and the pointer during the hand setting operation.

2. In sighting apparatus for guns, the 100 combination with the range dial and its pointer, of a motor controlled from a distance for actuating said pointer, hand actuated means for setting the range dial with respect to the pointer and changing the elevation of the sights, and means for automatically varying the relative movement of the range dial and the pointer during the hand setting operation.

3. In sighting apparatus for guns, the 110 combination with the range dial and its pointer, of an electric motor controlled from a distance for actuating said pointer, hand actuated means for setting the range dial with respect to the pointer and changing the elevation of the sights, and means for automatically varying the relative movement of the range dial and the pointer during the hand setting operation.

4. In sighting apparatus for guns, the 120 combination with the range dial and its pointer, of means for actuating said pointer from a distance, hand actuated means for setting the range dial with respect to the pointer and changing the elevation of the sights, means for automatically varying the relative movement of the range dial and the pointer during the hand setting operation and means whereby the extent of such relative movement can be controlled in accord- 130

ance with the corrections to be made in the sight setting.

5. In sighting apparatus for guns, the combination with the range dial and its pointer, of a motor controlled from a distance for actuating said pointer, hand actuated means for setting the range dial with respect to the pointer and changing the elevation of the sights, and means for automatically varying the motion of the pointer during the hand setting operation.

6. In sighting apparatus for guns, the combination with the range dial and its pointer, of a motor controlled from a distance for actuating said pointer, hand actuated means for setting the range dial with respect to the pointer and changing the elevation of the sights, means for automatically varying the motion of the pointer during the hand setting operation, and means whereby the extent of such variation of the pointer's motion can be controlled in accordance with the corrections to be made in the sight setting.

7. In sighting apparatus for guns, the combination with the range dial and its pointer, of a motor controlled from a distance for actuating said pointer, hand actuated means for setting the range dial with respect to the pointer and changing the elevation of the sights, a double armed or bell crank lever of which one arm or member engages with a cam or spiral groove of the range dial, an adjustable piece mounted on the other arm or

member of said lever, and means whereby the position of the adjustable piece affects the extent of movement imparted to the pointer by the motor during the hand setting operation.

8. In sighting apparatus for guns, the combination with the range dial and its pointer, of a motor controlled from a distance for actuating said pointer, a casing inclosing said motor and adapted to move about the axis of the range dial, hand actuated means for setting the range dial with respect to the pointer and changing the elevation of the sights, a double armed or bell crank lever of which one arm or member engages with a cam or spiral groove of the range dial, an adjustable piece mounted on the other arm or member of said lever, and means whereby in accordance with the position of the adjustable piece and the degree of motion imparted to the range dial during the setting of the sights by the hand actuated means, the casing of the motor will receive angular movement and thus affect the extent of motion transmitted to the pointer by the motor.

In testimony whereof we affix our signatures in presence of two witnesses.

ARTHUR TREVOR DAWSON.
GEORGE THOMAS BUCKHAM.
